UNITED STATES PATENT OFFICE

ALBERT C. ERNEST, OF HUBBARD, TEXAS, ASSIGNOR, BY DIRECT AND MESNE ASSIGNMENTS, TO STEVE C. WALLACE, OF COOLIDGE, TEXAS.

PROTRACTOR.

1,159,483.

Specification of Letters Patent.

Patented Nov. 9, 1915.

Application filed April 17, 1914. Serial No. 832,551.

To all whom it may concern:

Be it known that I, ALBERT C. ERNEST, citizen of the United States, residing at Hubbard, in the county of Hill and State of Texas, have invented certain new and useful Improvements in Protractors, of which the following is a specification.

This invention relates to protractors and more particularly to a protractor or gage for use by carpenters in cutting the rafters for a building roof, the aim of the invention being to provide an instrument of this class which will obviate the use of the ordinary carpenter's square in obtaining the desired measurements and in determining the angles at which the ends of the rafters are to be cut, and which will further obviate the necessity of a carpenter making calculations which are necessary if the ordinary square is to be employed.

In the accompanying drawings: Figure 1 is a perspective view of the instrument embodying the present invention. Fig. 2 is a plan view of one side thereof. Fig. 3 is a similar view of the other side. Fig. 4 is an edge view of the instrument.

Corresponding and like parts are referred to in the following description and indicated in all the views of the accompanying drawings by the same reference characters.

The instrument comprises a stock consisting of spaced plates 1 which are of counterpart outline and which have parallel edges. The plates 1 are spaced apart at one end by means of a spacing strip 2 although the stock may be cut from a single piece of material if desired. The instrument also includes a blade which is indicated by the numeral 3. The blade 3 is substantially triangular, its side edges indicated one by the numeral 4 and the other by the numeral 5 extending at an angle of 90 degrees with respect to each other. The blade at the base of the triangle, however, is approximately rectangular, this portion being indicated by the numeral 6 and being of a width equal to the width of the stock 1 so that the blade may be positioned with its said portion 6 housed between the plates comprising the stock. At one corner the blade is pivotally mounted between the ends of the plates 1 opposite the ends which are spaced by the strip 2 by means of a bolt or rivet 7 passed through the said ends of the plates 1 and through the said corner of the blade. It

will now be apparent that the blade may be adjusted angularly with respect to the stock, and it is in fact contemplated that the blade shall be so adjusted so as to bring certain scale marks on its faces into registry with the edges of the plates comprising the stock whereby to secure a certain definite angular adjustment of the blade with respect to the stock, so that when the stock is disposed against the work to be cut, the line of cut may be marked upon the work by running a pencil along one or the other of the edges 4 and 5 of the blade.

The face of one of the plates 1 comprising the stock is divided by intersecting lines extending lengthwise and transversely of the said face, into columns, at the upper end of each of which columns is marked a numeral indicating the width of the building in feet, these width indications extending in numerical order in a series from the inner to the outer end of the blade, as for example, the numerals 4, 6, 8, etc., indicated at 8 in Fig. 2 of the drawings. At that end of the series of columns next adjacent the inner end of the stock there is located a column 9, and in this column is arranged a series of indications denoting the pitch of the roof to be constructed, as for example, 6x12, 8x12, etc. In each of the columns headed by the indications denoted by the numeral 8 there is arranged a column of numerals indicating in feet and inches the lengths of the various common rafters. For example, at the intersection of the column headed by the numeral 6 with the longitudinally extending column at the end of which appears the pitch indicated 6x12, we find the numerals 3.4, which indicate that if the span of the roof is to be 6 feet and the pitch is to be 6x12, the length of the common rafter will be 3 feet, 4 inches. The portion 6 of the blade 3 at the corresponding side of the instrument is likewise divided into a number of columns, corresponding to the columns 8 previously referred to and indicated here by the numeral 11, and into a column 12 bearing at one end the word "Span," this column having therein a number of numerals indicating the span of the roof. In each of the columns 11 of the table now referred to is arranged a series of numerals designating the lengths of the different hip rafters. For example, if the building is 10 feet wide

and the pitch is 6x12, the length of the hip rafter will be 7 feet, 6 inches.

Referring now to Fig. 3 of the drawings, it will be observed that the face of the other plate 1 is divided into a number of columns 13, these columns being divided by lines 14, each into a number of spaces as in the case of the first and second described scales, and in the column 13 at the inner end of the 10 blade is arranged a series of numeral combinations indicating the pitch of the roof. The other columns 13 are headed by numerals indicated at 15, denoting the span of the roof and in the spaces of these columns are numerals indicating in feet and 15 inches the lengths of the different octagon hip rafters. For example, if the span is 8 feet and the pitch of the roof is 6x12 we find that the octagon hip rafter will be 4 20 feet, 9 inches in length. Other columns 16 are also marked off upon the said face of the blade and between the series of columns 13 and 16, or in other words, at the inner ends of the series of columns 13 and 16, 25 there is printed the legend "Length of octagon jack," or some other appropriate heading to indicate that the numerals in the columns 16 denote in feet and inches the lengths of the octagon jack rafters.

30 Returning now to Fig. 2 of the drawings, it will be observed that the first-mentioned face of the blade 3 is divided into a number of columns extending parallel to the edge 4 of the blade, one of these columns being indicated by the numeral 17, another by the 35 numeral 18, a third by the numeral 19 and a fourth by the numeral 20. Within the columns 17, 18, 19 and 20 is marked a number of lines 21, 22, 23 and 24 respectively, 40 these lines extending tangentially with respect to a circle having the rivet 7 for its center and touching the base line of the triangular portion of the blade, the said base line of this portion being indicated specifically by the numeral 25. The column 17 is headed by a legend, such for example, as "Pitch of common rafter," the column 18 is headed by a legend, such for example, as "Pitch of hip rafter," the column 19 by a 45 legend, such for example, as "Side cut of jack rafter," and the column 20 is headed by a legend, such for example, as "Side cut of hip on ridge," and the lines 21, 22, 23, and 24 in the said columns 17, 18, 19 and 20, 50 are marked with numeral combinations referring directly to the legends at the heads of the columns. Adjacent the edge 4, the said face of the blade 3 bears legends, as for example "Top cut of rafters" and "Backing of hips" indicating that this edge is to be employed in the marking of these cuts of the rafters, the blade having been of course previously adjusted so that the proper ones of the lines 21, 22, 23 and 24, 55 as the case may be, may register with the

edge of the stock. In a like manner the blade bears a legend adjacent the edge 5 thereof, as "Bottom cut of all rafters," indicating that a pencil or other marking instrument is to be drawn along this edge in making all bottom cuts and side cuts.

The other face of the blade 3 is divided into a number of columns which extend parallel to the edge 4 as do the columns 17, 18, 19 and 20, above described, and these last-mentioned columns are indicated by the numerals 26, 27, 28, 29 and 30. The columns 26, 27, 28, 29 and 30 respectively bear legends "Pitch of octagon hip," "Side cut of octagon hip on ridge," "Side cut of octagon jacks," "Side cut for polygon" and "Miter cut for polygon," and the several columns are divided by a number of radially extending lines 31, 32, 33, 34 and 35 respectively, these several lines being marked with designations bearing relation to the several legends as will be readily understood. The other side of the blade 3 is preferably provided with a scale 36, the scale marks of which are indicated by numerals denoting the angular relation of the edges 4 and 5, as the case may be, to the stock at various angular adjustments of the blade upon its pivot 7, so that the instrument may be employed also as a bevel gage or for determining the angle of any bevel cut. Furthermore, the said face of the blade adjacent the edge 5 is preferably marked with a legend, as for example, "Make all side cuts here," and adjacent its edge 4 with a legend, such for example, as "Top cut of rafter," "Polygon gage cut here." It will be understood of course that while the arrangement of the scales herein shown is the preferred arrangement, the same may be varied within the 105 terms of the appended claim without departing from the spirit of the invention.

While, as before stated, the pivot 7 may be in the form of a bolt or a rivet, it is preferable that it be a bolt and provided with a 110 thumb nut 7^a which may be tightened for the purpose of binding the plates comprising the stock against the side of the blade 3 so as to hold the blade at any of its numerous adjustments.

In using the instrument, the blade is angularly adjusted between the spaced portions of the stock so that the scale marks of the several diagonal series upon the blade may be brought into registration with that 120 straight edge of the stock which lies at the top of the several columns of numerals which are marked upon the stock, and which have been previously referred to, and it will be understood that the said straight edge of either of the spaced portions of the stock is to be disposed against the work and that a pencil or other marking instrument is to be drawn along one or the other of the edges 125 of the triangular portion of the blade.

Having thus described the invention what is claimed as new is:

In a device of the class described, a stock having a straight edge and a blade having substantially the form of a right angle triangle and pivoted at one corner to the said stock, the side edges of the blade constituting marking edges, one face of the blade being provided with a plurality of lines extending parallel to that side edge of the blade remote from the pivot and dividing the said face into a series of spaces, the said

face of the blade being provided within each of said spaces with a series of scale marks designed to register with the straight edge 15 of the stock when the blade is moved upon its pivot.

In testimony whereof I affix my signature in presence of two witnesses.

ALBERT C. ERNEST. [L. S.]
